UNITED STATES PATENT OFFICE

EUGENE WASYLENKO, OF CHESTER, PENNSYLVANIA

APPARATUS FOR DEVELOPING AND PRINTING PICTURES

Application filed September 26, 1929. Serial No. 395,441.

This invention relates to improvements in apparatus for developing and printing pictures of the kind usually supplied in packs.

The primary object of this invention is to provide a compact apparatus adapted to perform both printing and developing of the negative film, without making ready for a lot of other apparatus.

A still further object of this invention is to provide a device of the above character adapted to be carried from one place to another without requiring other instruments to perform the necessary operations on the film negative.

A still further object of this invention is to provide a device of the above mentioned character adapted to accommodate the usual type of roll pack films of any desired size or dimension.

A still further object of this invention is to provide a device of the above mentioned character which may be cheaply and economically manufactured and which may be operated by an amateur photographer with remarkable ease.

Other objects and advantages of the invention will become apparent during the course of the following description forming a part of this specification and in which,

Figure 1 is a top plan view of the invention showing the general arrangement of parts;

Figure 2 is a side elevational view of the invention showing the crank arm and locking device for the roll reel;

Figure 3 is a longitudinal top elevational view of the invention showing the cover removed to illustrate the relative interior mechanism;

Figure 4 is a transverse cross-sectional view of the invention showing one of the film holding spools and its manner of operation;

Figure 5 is a perspective view of the locking device for locking the shaft which is also shown in perspective;

Figure 6 is a fragmentary transverse cross-sectional view of the spool drive connection;

Figure 7 is a longitudinal cross-sectional view of the invention in assembled relation showing the manner of driving the film holding spools and the developing tank;

Figure 8 is a similar view showing the film holding spools and the manner of arranging the film for developing; and

Figure 9 is a view of the same showing the manner of arrangement for printing.

In the drawings forming a part of this specification wherein is shown for the purpose of illustrating the invention, the numeral 5, designates a receptacle formed of wood or other material and is made waterproof by a hard rubber receptacle 6 which is snugly fitted into the dimensions of the outer receptacle 5. A cover 7 is provided and is chambered at 8, on its side and end walls to receive the free edge of the waterproof container 6. On each of the sides of the cover 7 is mounted a plate 9, by means of wood screws, for providing pivoted latches 10, adapted to engage hooks 11, formed on the plates 12, which are secured to each side of the receptacle 5.

The cover 7 is also provided with a longitudinal rib 13 for forming a space 14 between one of the side walls whereby a compartment 15 is formed. Mounted at opposite ends of the compartment 15 is a pulley 16 mounted upon shaft 17 and also supported in openings 18 and 19 formed in the longitudinal rib 13 and the side wall respectively as more clearly shown in Fig. 6. Upon the shaft 17 is mounted a coil spring 20 in order to extend the enlarged portion 21 of the shaft 17 into engagement with a present day film roll which is designated as at 22 and is provided with the usual metal flange 23 and the usual opening 24 and having the film receiving slot 25.

The construction above described, is the same at both ends of the receptacle cover 7 and both of the pulleys 16 are connected by means of a belt 26 which passes therearound and provides for the simultaneous rotation of the same in the same direction. Each shaft 17 is screw threaded as at 27 and is provided with a thumb nut 28 whereby a handle 29 may be secured to one or both of the shafts 17 as

the case may require. Threaded on one of the shafts 17 is a locking plate 29 having a longitudinal slot 30 with an intermediate enlarged portion 31 for receiving the shaft 17. The sliding lock 29 is mounted upon the

100

cover 7 at the side portion thereof by screws 32 and it is provided with an operating finger piece 33 whereby the same may be reciprocably slid. A reduced portion 34 in one of its shafts 17 is provided whereby the specific portion of the slot 30 may be therein received for holding the shaft 17 in its operative position whereby the enlarged end 21 of the shaft will be selectively secured to the film roll or 10 spool 22.

A pair of downwardly descending film supports 36 are provided adjacent the film holding spool 22 whereby the film will be guided downwardly from the roll and in close relation to the water proof container 6. The 15 guiding rods 36 are secured to the cover 7 by means of screws 27 and the film engaging portions of the guides 36 are arcuately curved to conform to the general contour of the sets 20 of films.

A freely rotatable roll 40 is removably secured to the longitudinal rib 13 at one of its side walls by spring clips 41 engaging the usual type of opening formed in the ends of 25 the wooden roller 40. The roll 40 is provided with metallic end flanges 42 which are also of the usual construction.

It will be noted that the opposite ends of the film holding spools 22 are engaged by 30 spring members 43 mounted in a cut-away portion 44 in one side of the cover 7 and held thereto by means of a screw 45 which passes through a flanged portion 46 of the spring member 43. The spring member 43 35 is also provided with a lug 47 which is adapted to engage in the end opening 48 of the roll 22. The cover 7 is provided with a flexible handle 50 secured by strap end attaching devices 51 to the side wall of the cover whereby 40 the device may be easily carried from place to place. In the top wall of the cover 7 is provided angular openings 52 which are presented at an angle to the film holding spools whereby the film from the spool may be directed through the opening 52 and across a 45 portion of the cover 7 for the purpose of printing.

A filler spout 53 is shown as communicating with the cover 7 and the filler spout 53 50 is provided with a goose neck which terminates in the side wall of the receptacle as at 54 whereby the receptacle may be filled with the usual developing liquid.

Any means may be provided for bracing 55 the longitudinal rib 15 and as shown a frame supporting bar 55 is employed and has its opposite ends secured to the longitudinal rib 15 and one side of the cover by means of wood screws 56.

For the purpose of illustrating the operation of the device attention is directed to 60 Figs. 8 and 9 wherein are shown the films to be developed and printed secured in operative position. Figure 8 illustrates the first 65 step of developing a film and as shown, the

film pack on the spool 40 is the usual type of film spool adapted to fit different dimensions of cameras and which may be removed therefrom and placed directly in the cover 7 by means of the spring clip 41. Usually in

this type of film spool, the negative is protected by means of a cover strip A which is formed of ordinary dark paper and is only for the purpose of protecting the coiled surfaces of the negative strip B. One end of the 75 negative strip B is secured to one of the film spools 22, while the other black paper strip A is secured to the adjacent film spool 22 for the purpose of removing the blank paper from the negative. At the same time when 80 this operation is going on, the negative B is being developed in the tank 6 in which is placed the usual developing fluid well known in the art. After the protective covering or paper A has been removed from the negative 85 film B and the negative film B has been wound upon one of the rollers 22 which is at the farther end of the cover 7, the same spool is removed and is exchanged for the opposite spool 22 as shown in Figure 9. The same is 90 placed on the rotatable shaft 17 in exchange for the rolls which unwind the protective covering from the film pack originally contained on the spool 40. The spool 40 is then provided with a printing paper B which is 95 threaded upwardly through one of the openings 52 and downwardly through the remote opening 52 of the cover 7 whereby the end is secured to an empty spool mounted on the shaft 17. After the printing paper B has 100 been placed in position, the negative B is also threaded upwardly through one of the openings 52 which places it above the printing paper for printing the negative B. The ends 105 of the printing paper B and the negative B are both secured to the same opposite roll and are supposed to be simultaneously wound thereupon, after which they are separated while receiving the fixing solution which is well known and common in the art.

It is to be understood that various changes in the shape, size and arrangement of parts shown and described may be resorted to without departing from the spirit and scope of the invention or the scope of the subjoined claims. It is also to be understood that the shape and construction of the film supporting rollers are of usual construction as sold or furnished with a pack of films when the same are purchased.

I claim:

1. In a device for preparing and printing films, comprising a container adapted for holding a developing fluid, a cover for the receptacle having transverse openings in its upper wall, and means for directing a film negative into close engagement with the bottom of the receptacle or through the transverse openings in the cover.

2. In a device of the character described,

a waterproof receptacle, adapted for holding a developing fluid, a slotted cover for said receptacle, means associated with the cover for guiding a film strip negative into close engagement with the bottom of the receptacle and said strip adapted to be directed through the cover slots, whereby the film negative may be developed and printed.

3. A developing and printing device for negative film strips, comprising a waterproof receptacle adapted to contain a developing solution, a cover for the receptacle having transverse openings formed in the upper wall thereof, a film holding spool at one end of the cover, a pair of film holding spools at the opposite end of the cover and means for rotating the first mentioned film holding spool in unison with one of the second named spools, whereby the negative strip may first be directed into the waterproof receptacle for developing or through the transverse openings in the cover for printing.

4. A developing and printing device for roll pack films, including a waterproof receptacle, a fluid inlet associated with the receptacle, a cover for the receptacle, means for holding the cover into engagement with the receptacle, said cover having a pair of spaced transverse openings formed therein for allowing free passage of the negative film, a film holding spool mounted at one end on the interior of the cover, a pair of film holding spools at the opposite end thereof, means for driving the first mentioned film holding spool in unison with one of the film holding spools at the opposite end of the cover, a downwardly depending guide bar secured to the cover adjacent each of the above driven film holding spools, and removable means for holding the film holding spools in their operative position whereby the film holding spools may be easily removed.

5. In a device of the character described, a waterproof container, having a fluid inlet, a cover associated with the receptacle, a film holding spool mounted in one end of the cover, means for removably holding the film holding spool, a pair of film holding spools in the opposite end of the container, means for driving the first mentioned film holding spool in unison with one of the second mentioned film holding spools at the opposite end of the cover, whereby one of the second mentioned spools may be employed for the winding of the printing paper onto the negative film strip, or for removing the protective film strip, or for removing the protective paper cover from the film roll as it is manufactured, and means for detachably holding the film holding spools whereby they may be removed and placed in opposite ends of the cover for manipulation of the film strip.

6. A device of the character described for

developing and printing negative films comprising a waterproof receptacle having a liquid filling opening, a cover for the receptacle having a pair of transverse spaced openings, a longitudinal rib extending the length of the cover, a film holding spool associated with one end of the cover, mounted between the longitudinal rib and one of the side walls of the receptacle, a pair of film holding spools mounted at the opposite end of the cover, and means for driving the first mentioned film holding spool and one of the second mentioned film holding spools.

In testimony whereof I affix my signature.
EUGENE WASYLENKO.
